UNITED STATES PATENT OFFICE.

JOHN F. ISAACSON, OF CHICAGO, ILLINOIS.

HEEL RANDING AND TRIMMING MACHINE.

SPECIFICATION forming part of Letters Patent No. 515,492, dated February 27, 1894.

Application filed July 15, 1893. Serial No. 480,671. (No model.)

To all whom it may concern:

Be it known that I, JOHN F. ISAACSON, a citizen of the United States, residing at Chicago, in the county of Cook and State of Illinois, have invented certain new and useful Improvements in Rand and Heel Trimming Machines, of which the following is a specification.

The object of this invention is to construct a machine in which is supported a revolving rand cutter and a revolving heel trimmer, and a support for the material to be operated upon made movable to properly present it to cutters.

In the accompanying drawings,—Figure 1, is a face elevation of my improvements. Fig. 2, is an edge elevation thereof. Fig. 3, is an inner face view of the cutter supporting frame. Fig. 4, is an inner face view of the frame for supporting the material. Fig. 5, shows the means for adjusting the toothed rack. Figs. 6, 7 and 8 show the material in the various stages of completion. Fig. 9, is a vertical lengthwise section through the heel pile and operating mechanism.

The supporting frame for the cutters in this instance consists of the plates 1, and 2 connected by a base plate 3. In suitable bearings in these upright plates are supported a shaft 4, to which is connected a heel trimming cutter 5, a shaft 6, supporting a saw 7, and a main driving shaft 8, to the outer end of which is secured a pulley 9, and between the plates is secured a pulley 10, a band 11, connecting it with a pulley 12, supported by the shaft 6, which also supports a larger pulley 13, having a connection with the pulley 14, supported by the shaft 4, by a band 15, the band being crossed to impart motion to the various parts in the proper direction.

From the plate 1, extend two shafts 16 and 17, the free ends of each and the shaft 8, supporting grooved edged rollers 18, and to the face of the plate is secured a toothed rack 19, by a set screw 20, passing through a slot 21, in the plate, a stud 22, extending from the rack moves in a slot 23, giving direction to the adjustment of the rack, as shown at Figs. 3 and 5. Upon the shaft 16, is supported a sleeve to which is secured at one end a sprocket wheel 24, and to the other end an arm 25, from which projects a stud 26, and

upon the shaft 4, outside of the plate 1, is secured a sprocket wheel 27, having a chain belt 28, connecting it with the sprocket wheel 24. To the face of the sprocket wheel 27, is secured an arm 29, supporting a toothed wheel 30, at its free end which meshes with a like toothed wheel 31, secured to the end of the shaft 4, and to its face is secured a rand cutter 32.

The face plate 33 is placed over the plate 1, of the main supporting frame and is provided with three irregular shaped openings 34, the center portion 35, held in position by 65 the bridges 36. The center of one of these centers being cut out as shown at 37. The grooved edged rollers 18, are located in these openings so that the flanges of the rollers will engage each face of the plate, the center portion of the rollers fitting within the openings. The roller located on the main driving shaft 8, has a toothed wheel 38, secured to its rear face the teeth of which mesh with series of teeth or pins 39, extending from the inner 75 face of the plate 33, corresponding in outline with the irregular shaped openings 34.

The plate 33, is provided with an opening 40, corresponding in shape to the lift of the heel, and to the outer face of this plate around 80 the opening is secured a trough or guide 41. To the inside of this plate is secured a roller 42 being located over the opening 40, the bearings 43 supporting the roller being slotted in order that the roller may be vertically adjustable. A shaft 44, is also located in bearings secured to the inside face of plate 33, and curved rollers 45, are adjustably secured to this shaft, their curvature corresponding in shape to the curved portion of the heel of 90 the shoe. To one end of this shaft is secured a toothed wheel 46.

The operation of my device is as follows: The leather 47, composing the heel is cut to the desired shape and size of the greatest lift 95 of the heel, and a number of such lifts are glued together as shown at Fig. 6, and when desired is placed in the trough and projecting beyond the inner face of the plate 33, until even with the face of the toothed wheel 100 30, when the parts will appear in the position shown in the drawings. Motion being imparted to the driving shaft by connecting the pulley 9, with a suitable prime mover, a

rotary motion will be imparted to the heel trimming knife 5, to the rand cutter 32, and to the saw 7. The rotary movement of this shaft will cause the toothed wheel 38, to revolve and owing to its shaft being held in a position relatively with its supporting frame, the front plate 33, will move first in an upward direction corresponding to the shape of the openings 34, the lower portion of which being the same as the opening 40, through which the material is presented. The position of the heel trimming knife with relation to the material is such that it will revolve in contact with the material on its two vertical and bottom surfaces cutting away so much of the material necessary to the proper shape of heel as shown at Fig. 7. While the knife is trimming the outside of the heel the rand cutter follows the curvature of the heel and owing to the shape of the cutter the material will be dished out as shown at Fig. 7, when the material is brought in contact with the rotating saw 7, which will sever the formed heel from the balance of the material, leaving the end of the material smooth, when the finished heel will appear as shown at Fig. 8.

At the point of severing the heel from the material the rollers will be at the opposite end of the upper portion of the openings 34, and while the roller is traveling this upper portion of the openings the material will be withdrawn clear of the saw, and the toothed wheel 46, brought into engagement with the toothed rack 19, when the positions of the parts will be that shown in the drawings. During that portion of the vertical movement of the front plate at the commencement, the toothed wheel 46, will travel up the toothed rack imparting a rotary movement to the shaft 44, and to the wheels 45 supported thereby, and as the material rests upon these wheels and against the under face of the roller 42, it will be fed toward the knife and cutter the proper distance for a new heel, by this time the toothed wheel 46, has run off the upper end of the toothed rack

stopping the further feeding of the material, when the operation of forming the rand and trimming the heel will again be repeated.

At the commencement of the operation of the machine the knife and cutter will occupy the positions shown at Fig. 3, and in order that the rand cutter will follow the curved portion of the heel, the pin 26, travels in the inside opening 37 which will cause a partial revolution of the sprocket wheel 24, and the chain belt will transmit this motion to the rand cutter which will always hold the knife and cutter in proper position, that each may do its work.

When the height of the heel is varied the heel trimming knife must be changed and the toothed rack adjusted to regulate the feed of the material and the saw adjusted to cut off the finished heel at the proper point.

The wheels 45, are adjusted on their supporting shaft to properly fit the curvature of the heel.

A curved knife may be employed which will give a corresponding appearance to the finished heel.

By means of this device I am able to produce a series of finished heels from the material glued up in the manner above set forth.

By the employment of the three irregular shaped openings 34, the plate 33, is always held in a vertical plane in order to present the material to be operated upon in a proper manner.

I claim as my invention—

In a heel randing and trimming machine, the combination of a support for the material to be operated upon, means for feeding the material a rotary knife for trimming the heel, a rotary cutter for producing the rand, a rotary saw standing in a plane at right angles to the material for cutting off the finished heel, and driving mechanism for the various parts.

JOHN F. ISAACSON.
